UNITED STATES PATENT OFFICE.

WILLIAM L. LUKENS AND RAYMOND R. CAREY, OF BETHLEHEM, PENNSYLVANIA,
ASSIGNORS TO BETHLEHEM STEEL COMPANY.

FUSE FOR PROJECTILES.

Application filed February 3, 1926. Serial No. 85,638.

Our invention relates to impact fuses for projectiles and particularly to the type of fuse described and shown in application, Serial No. 713,514, filed May 15, 1924, and assigned to the Bethlehem Steel Company.

In fuses of the above mentioned type there is provided a firing mechanism, comprising a movable striker element and a movable member carrying a firing element, which is moved during the flight of the projectile, from a normal or safe position to an effective or firing position, and, during such movement, said member also carries a detonator normally disposed in a remote position relative to the booster charge to a position in close proximity to the latter. It has been found under certain conditions at impact of the projectile with a target, particularly so at a comparatively light impact, that a rigid support is not afforded to the firing element sufficiently to retard the blow of the striker and cause the firing of the firing element, that is, the latter recedes before the blow of the striker, thus rendering such blow ineffective. Furthermore, if a comparatively heavy impact is encountered, the forces occasioned by impact may be sufficient to return the detonator towards its normal or safe position and thus render it ineffective to correctly detonate the booster charge. An object of our invention is the provision of a detent device which is adapted to function when the firing member is moved forwardly, and positively prevents the return or rearward movement of the latter member towards its safe or unarmed position.

Another object of our invention is the provision of a novel safety chamber construction which effectively prevents the propagation of the wave of detonation from a prematurely exploded detonator to the booster charge when the fuse is in a safe or unarmed condition, but which, however, is so constructed that the passage of flame of detonation from the detonator to the booster charge is unhindered when the detonator is moved forwardly, during the flight of the projectile, to its firing position.

Broadly stated, our invention comprises a detonating fuse having a movable firing element, a detent device adapted to function, when the firing element is moved to its firing position, to engage a fixed abutment and thus provide a rigid support for said element to effectively resist the impact blow

of the striking element and furthermore to positively prevent the return movement of said element to its safe or unarmed condition.

The novel features will be more fully understood from the following description and claims taken with the drawings, in which:

Fig. 1 is a longitudinal cross section showing a detonating fuse, embodying our invention, in its safe or unarmed condition;

Fig. 2 is a similar view to Fig. 1, illustrating the fuse in its condition at the instant of impact;

Fig. 3 is a side elevation of the detent device;

Fig. 4 is an end view of the detent shown in Fig. 3;

Fig. 5 is a partial side elevation of the safety expansion chamber;

Fig. 6 is a partial section of the safety expansion chamber showing a modification in the wall construction thereof; and,

Fig. 7 is a partial section illustrating an alternative detent device.

Referring to the drawings, 10 indicates a fuse body bored axially to form therein a plurality of recesses 11, 12 and 13, respectively, to receive the firing mechanism and booster charge.

Threaded in the recess 11 is an annular bushing 14 which extends forwardly beyond the body and is threaded externally to receive a safety cap 15. The bushing 14 is provided with an internal shoulder 16 to normally prevent the rearward movement of the striker element 17 which is slidably mounted therein. The striker is provided with a reduced cylindrical portion 18 which extends rearwardly into the recess 11, beyond the shoulder 16, and has formed thereon a groove 19. At its rear end the striker is coned to form a needle 20. The recess 12 is threaded to receive the threaded end of the safety expansion chamber cylinder 21 which is mounted concentrically in the recess 13. The cylinder 21 is centrally bored to form the passage-way 22 which is enlarged in diameter at the rear end of the cylinder to provide an expansion chamber 23. The latter is threaded to receive the screwed base plug 24 which constitutes a closure for the chamber. The annular space between the cylinder 21 and the wall of the recess 13 contains a booster charge 25 of a suitable explosive material which is supported on the plug 26 threaded to the base of the body, said plug constituting a closure for

the recess 13. The cylinder 21 is provided with a plurality of radial recesses 27 which contain a high explosive material similar to the booster charge. The recesses 27 are open to the exterior of the cylinder and are bored to such depth that there is a thin wall of material 28 provided to normally prevent communication between the chamber 23 and the recesses 27. In Fig. 6 we show a modification 10 in the construction of the cylinder wall. In this modification the recesses 27 are bored through the wall of the cylinder and a shoulder 27' is formed in said recesses. A disc 28' is pressed in place against the shoulder 27' and constitutes closures for said recesses.

An apertured diaphragm 21' is disposed between the end of the cylinder 21 and a shoulder formed on the body 10 and is provided with an opening coaxial with but of somewhat less diameter than the diameter of the passageway 22 so as to provide an annular shoulder 30 which extends inwardly beyond the wall of the passageway. A detonator carrier 31 is slidably mounted in the passageway 22 and is provided with an annular shoulder 32 which engages the forward face of the diaphragm 21' to limit the rearward movement of said carrier. A collar 33 adapted to engage the shoulder 30 is formed on the latter member to limit its forward movement. The carrier 31 is bored axially to provide a flame conduit 34 which communicates the primer 35, mounted at the forward end of said carrier, with the detonator 36 crimped to the rear end thereof. A cylindrical safety cage 37 is interposed between the carrier 31 and the striker 17 so that the forward movement of the former causes a corresponding movement of the latter. The cage 37 is indented circumferentially at its rear end to provide an annular abutment 38 which engages the forward end of the carrier 31.

The wall of the cage 37 is slit longitudinally for a distance from its forward end to provide a plurality of resilient fingers 39 which are indented circumferentially at their forward ends to yieldingly engage the groove 19 formed in the striker 17. The extreme ends of the cage 37 are flared outwardly beyond the periphery of the cage and normally engage the wall of the recess 11 to rigidly maintain the fingers 39 in clamping relation to the striker 17 and thereby prevent relative movement between the cage and the striker 17 until the firing mechanism is moved forwardly a predetermined distance to its firing position, as hereinafter described.

In order to prevent the movement of the firing mechanism before the projectile is fired from a gun there is provided an inertia safety arrangement comprising a stirrup member 40 and an annular inertia member 41. The latter surrounds the carrier 31 and its forward face normally abuts the end of the recess 12. The stirrup member 40 is crimped to the for-

ward end of the carrier 31 and its rearwardly extending legs 42 are flared outwardly to normally engage the rearward face of the inertia member 41 and thus prevents the forward movement of the carrier 31. In order to normally prevent the forward movement of the cage member, leg portions (not shown) extend rearwardly between the legs 42 of the stirrup 40 and engage the bottom face of the inertia member 41, such feature being clearly shown and described in the aforementioned pending application. A coil spring 43 is interposed between the inertia member 41 and the diaphragm 21'.

The detent member 44 comprises a cylindrical body portion 45 and a plurality of resilient finger portions 46 which are bent radially outward from the body portion and obliquely thereto. The body portion 45 is crimped in a groove 47 formed in the carrier 31 and the finger portions extend outwardly from the latter. Referring to Fig. 7 we show an alternate detent device comprising a split resilient ring 44' which is sprung over the carrier 31 and engages in the groove 47' formed in the carrier. The ring 44' is normally maintained under initial compression by the diaphragm 21'.

Assuming the fuse to be in a safe or unarmed condition, as shown in Fig. 1, and assuming that the detonator explodes prematurely, the strong walls of the chamber 21 would contain the gases generated by such explosion and any gases which may escape through the clearance between the walls of the passageway 22 and the carrier 31 would not have sufficient strength to rupture walls 28 at the bottom of the recesses 27.

Before loading the projectile into the gun the cap 15 may be removed if a light impact is expected. However, if a heavy impact is to be encountered the fuse will function without the removal of the cap.

When the projectile is fired and during the initial acceleration thereof, the member 41, due to its inertia, moves rearwardly relatively to the forwardly moving parts, compresses the spring 43 and at the same time disrupts the legs 42 of the stirrup 40 which still retain a certain amount of resiliency so that when the member 41 has reached its rearward position, said legs spring outwardly into the groove 48 formed in said member. At the cessation of the acceleration of the projectile the spring 43 returns the inertia member 41 to its original position and due to the engagement of the stirrup 40 with said member the carrier 31 is moved forwardly into the position shown in Fig. 2. During the forward movement of the carrier 31 the finger portions 46 of the detent 44 squeeze through the opening formed in the diaphragm 21' and spring to their open position in front of the shoulder 30 when the carrier has reached its forward position. In our

modified construction shown in Fig. 7, when the carrier 31 is at its forward position the ring 44 is released from its engagement with the diaphragm 21' and it expands radially beyond the shoulder 30' of said diaphragm and thus prevents the return of the carrier to its original position. In this latter position of the carrier the detonator is placed in close proximity to the recesses 27 and, through the medium of the cage 37, the striker 17 is moved forwardly from the shoulder 16 and it will also be noted that the flared ends of the fingers 39 are placed opposite the annular recess 49 formed in the body 10. When the several parts are in the position just described, the fuse is in its armed condition; flared ends of the fingers 39 being opposite the recess 47 are no longer restricted against radial movement and the striker 17 is yieldingly supported thereby. At impact the striker 17 is forced rearwardly, spreading the fingers 39, and the needle 20 fires the primer

35. As shown in Fig. 2, the detent 44 engages the shoulder 30 and positively prevents the rearward movement of the carrier 31 and when the flash from the primer 35 explodes the detonator, the full force of detonation ruptures the thin wall 28 and is propagated by the high explosive material contained in 40 the recesses 27 to the booster charge 25, which, in turn, explodes the main charge of the projectile in the well known manner.

It will be seen from the foregoing description that we have devised a fuse for projectiles that is safe under normal conditions and positive in its action. At comparatively light impacts the primer is rigidly supported so that it receives the full effective blow of the striker and then again at comparatively heavy impacts the detonator is positively prevented from being returned from its armed to its safe position by the forces of impact.

While we have shown our invention in but two forms, it will be obvious to those skilled in the art that it is not so limited but is susceptible of various other changes and modifications without departing from the spirit thereof, and we desire, therefore, that only 50 such limitations shall be placed thereupon as are imposed by the prior art or as are specifically set forth in the appended claims.

Having thus described our invention what we claim as new and desire to secure by Letters Patent is:

1. In a fuse for projectiles the combination with a fuse body, of a firing mechanism slidably mounted in said body, means to move said mechanism relatively to said body during the flight of the projectile, and means to positively prevent the return movement of a portion of said mechanism.

2. In a fuse for projectiles the combination with a fuse body, of a striker member slidably mounted in said body, a primer carrier slid-

ably mounted in said body, a safety member normally separating said striker and said carrier, means to move all of said members relatively to said body during the flight of the projectile, and means to positively prevent the return movement of said primer carrier.

3. In a fuse for projectiles the combination with a fuse body, of a striker member slidably mounted in said body, a primer carrier slidably mounted in said body, a safety member normally preventing relative movement between the striker and the carrier, means to normally prevent the movement of the carrier relative to said body but rendered ineffective during the acceleration of the projectile, means energized during said acceleration for moving said carrier relative to said body during the flight of the projectile, and means to positively prevent the return movement of said carrier towards its original position.

4. In a fuse for projectiles the combination with a fuse body, of a firing mechanism slidably mounted in said body, a hollow member disposed in said body and having a portion of its wall considerably weaker than the major portion thereof, a booster charge contained in said fuse body and surrounding said hollow member, a detonator normally disposed in said hollow member and in a position remote from said weakened portion and means adapted to move said detonator into close proximity to said weakened portion after the discharge of the projectile from the gun.

5. In a fuse for projectiles the combination with a fuse body, of a firing mechanism slidably mounted in said body, a hollow member mounted in said body and having a radially-disposed recess bored therein which extends from the outer periphery of said member but terminates short of the interior surface thereof, a booster charge contained in said body and surrounding said hollow member, a detonator normally disposed in said hollow member in a position remote from said recess, and means adapted to move said detonator into close proximity to said recess after the discharge of the projectile from a gun.

6. In a fuse for projectiles the combination with a fuse body, of a firing mechanism slidably mounted in said body, a hollow member disposed in said body and having a portion of its wall considerably weaker than the major portion of said wall, a booster charge contained in said body and surrounding said hollow member, a detonator normally disposed in said hollow member and in a position remote from said weakened portion, means adapted to move said detonator into close proximity to said weakened portion after the discharge of the projectile from a gun, and means to prevent the return of said detonator to its original position.

7. In a fuse for projectiles the combination with a fuse body, of a firing mechanism slidably mounted in said body, a hollow member mounted in said body, and having a radially-disposed recess formed therein which extends from the outer periphery of said member but terminates short of the interior surface thereof, a booster charge contained in said body and surrounding said hollow member, a detonator normally disposed in said hollow member and in a position remote from said recess, means adapted to move said detonator into close proximity to said recess after the discharge of the projectile from a gun, and means to prevent the return of said detonator to its original position.
8. A fuse for projectiles comprising a body, a firing mechanism, a hollow member mounted in said body and having a recess which extends from the outer periphery into close proximity to the interior surface of said member, a booster charge contained in said body and surrounding said hollow member, a detonator normally disposed in said hollow member and in a position remote from said recess, and means adapted to move said detonator into close proximity to said recess after the discharge of the projectile from a gun.
9. A fuse for projectiles comprising a body, a firing mechanism, a hollow member mounted in said body and having a recess which extends from the outer periphery into close proximity to the interior surface of said member, a booster charge contained in said body and surrounding said hollow member, a detonator normally disposed in said hollow member and in a position remote from said recess, means adapted to move said detonator into close proximity to said recess after the discharge of the projectile from a gun, and means to prevent the return of said detonator to its original position.
10. A fuse for projectiles comprising a body, a hollow member mounted in said body, and having a recess formed in the wall there-
- of, a booster charge contained in said body and surrounding said hollow member, a firing mechanism slidably mounted in said body and including a detonator normally disposed in said hollow member and in a position remote from said recess, means to normally prevent the relative movement between the body and said firing mechanism, rendered ineffective upon discharge of the projectile from a gun, means energized during the acceleration of the projectile for moving said firing mechanism whereby said detonator is moved into close proximity to said recess during the flight of the projectile, a shoulder formed on said body, and means to prevent the return of said detonator to its original position.
11. A fuse for projectiles comprising a body, a striker slidably mounted in said body, a primer carrier slidably mounted in said body, a safety member normally preventing relative movement between the striker and said carrier, means to normally prevent the movement of said carrier relative to said body but rendered ineffective during the initial acceleration of the projectile, a hollow member mounted in said body and having a recess formed in the wall thereof, a detonator carried by said carrier and normally disposed in said hollow member in a position remote from said recess, means energized during the initial acceleration of the projectile for moving said carrier relative to said body whereby said detonator is moved in close proximity to said recess, a shoulder formed on said body, and a resilient member fixed to said carrier adapted to pass said shoulder during the movement of the carrier but to engage said shoulder when said movement is completed so as to prevent the return of the detonator to its original position.
